UNITED STATES PATENT OFFICE.

BURTON S. AIKMAN, OF CHICAGO, ILLINOIS, ASSIGNOR TO NATIONAL BRAKE & ELECTRIC CO., OF MILWAUKEE, WISCONSIN, A CORPORATION OF WISCONSIN.

ENGINEER'S VALVE.

1,079,909.

Specification of Letters Patent. Patented Nov. 25, 1913.

Application filed March 7, 1910. Serial No. 547,888.

To all whom it may concern:

Be it known that I, BURTON S. AIKMAN, a citizen of the United States, residing at Chicago, in the county of Cook and State 5 of Illinois, have invented a certain new and useful Improvement in Engineers' Valves, of which the following is a full, clear, concise, and exact description, reference being had to the accompanying drawings, forming 10 a part of this specification.

My invention relates to engineers' valves, and has special reference to a form of valve adapted to be used in connection with fluid pressure brake systems.

15 In the so-called straight-air method of applying brakes, it is well known that the engineers' valve serves to establish connection between the main reservoir and brake pipe when the brakes are applied and between the brake pipe and atmosphere when 20 it is desired to release the brakes.

It is one of the objects of my invention to accomplish this result in a simple manner by the use of a device which is economical 25 to construct and efficient in operation.

When the fluid pressure brake system operates in the so-called "automatic" manner, by means of which the brakes are applied, by establishing connection between the 30 auxiliary reservoir and brake cylinder and released by exhausting from a cylinder pipe to the atmosphere, my improved form of engineer's valve can similarly be used, it being necessary merely to connect the cylinder 35 pipe to the engineer's valve in the manner in which the brake pipe was connected in the straight-air system, and to connect the brake pipe where the connection was made with the main reservoir.

40 For the sake of simplicity I will describe my invention as used in the straight-air system, it being always understood that if it is used in connection with an automatic brake system the connections can be made as 45 just described.

It is a further object of my invention to provide means by which the pressure in one of the chambers of the valve will always be maintained at the pressure of the main reservoir when the brakes are being applied, so that when connection is made with the brake pipe air will immediately flow into the same as desired and according to the cross-sectional area of the opening which is formed.

55 This result is accomplished by establishing

connection between the above mentioned chamber and the main reservoir before connection is established between the same chamber and the brake pipe. Conversely when connection is broken the opening between the chamber and the brake pipe is first closed, and, later, the connection between the main reservoir and the chamber is closed, thus leaving the pressure in the chamber the same as that in the main reservoir. On the other hand, when it is desired to connect the brake pipe with atmosphere, communication between the main reservoir and the above mentioned chamber is cut off by means of a suitable automatically operated valve, and the air in this chamber passes through a valve which is now opened into a second chamber, from which it is exhausted to the atmosphere, the connection being first established between the brake 75 pipe and the first chamber, and, subsequently, between said chamber and the passages which lead to the atmosphere. In this case it will be observed that the pressure in the chamber will remain the same as that in 80 the brake pipe, and in this way an irregular exhaust is prevented, which would take place if, for example, the connection with atmosphere were established before connection with the brake pipe. After the brakes 85 have been released and it is desired to make a new application, the pressure in the chamber will be again raised to that of the main reservoir before connection is made with the brake pipe in the manner which has already 90 been described.

These and other advantages of my invention will be more apparent by reference to the accompanying drawings in which—

Figure 1 is a front elevation of the engineer's valve; Fig. 2 is a vertical longitudinal section through the valve, showing certain parts in elevation and with the valve handle in position; Fig. 3 is a plan view of the lower portion of the valve casing, the upper portion of this casing and all operating parts being removed; Fig. 4 is a transverse sectional view through the upper chamber of the engineer's valve, showing the spindle and part of the connecting valve 95 in position; Fig. 5 is a transverse sectional and partly plan view showing the spindle and operating parts associated with the lower connecting valve, these parts being in the position which they would assume when 100 105 110

the parts in Fig. 4 are in the position shown; Fig. 6 is a partly sectional and plan view of the slide valve in the lower valve chamber; Fig. 7 is a side elevation of one of the connecting valves; and Fig. 8 is an end elevation of the connecting valve shown in Fig. 7.

The main valve casing consists of a lower portion 1 and an upper portion 2, in which 10 are the chambers 3 and 4, respectively. Mounted on the upper part of the portion 2 is the shield member 5, which, as shown in Fig. 1, is open in front. Within this shield member is the rotating collar 6, which 15 is integral with the engineer's handle 7. Within the handle 7 is the rod 8, normally held in engagement with a slot on the locking strip 9 on the casing 2 by means of the spring 10. Rigidly attached to the rotatable collar 6 is the spindle 11, which passes 20 downwardly through the casing 2, the chamber 4 and the chamber 3, engaging at its lower end the rotatable slide valve 12. In order to prevent the passage of fluid 25 from chamber 3 to chamber 4 the spindle 11 is provided with the collar 13, the gasket 14 being placed between the portions 1 and 2 of the main casing. As shown in Fig. 6, the lower end of the spindle 11 is triangularly shaped in order to engage the cross-members 15, 15 of the slide valve 12. A 30 recess 16 is formed within the end of the spindle 11, and a spring 17 is engaged against one end of this recess and on the other end engages the slide valve 12, thereby 35 serving to hold it firmly seated against the bottom of chamber 3. The slide valve 12 is provided with a round projecting lug 18 in its central portion which engages the recess 19 in the casing 1, and serves to hold 40 the valve 12 and the spindle 11 in a central position. Projecting downwardly from the portion 1 of the main casing are the pipe members 20 and 21, which are adapted for 45 connection with the brake pipe and a pipe in direct communication with the main reservoir by means of the coupling members 22 and 23.

Connected with pipe member 20 is the 50 passage 24 which terminates in port 25, this port being provided with notch 26, as shown in Fig. 3. Connected with the pipe member 21 is the passage 27, which is in direct communication with the valve chamber 28. This valve chamber is provided 55 with a bushing 29, within which the valve 30 is adapted to be operated, this valve being provided with packing 31, adapted to be seated on the seat 32 to break communication between chambers 33 and 28. The valve 30 is also provided with grooves 34', as shown in Figs. 7 and 8, thus affording free communication between all parts 60 of chamber 28. Passing through the opening 34 of the valve 30 is the valve stem 35,

and between the shoulder 36, of said stem and the nut 37 the valve 30 is securely clamped. The valve chamber 28 is closed at its outer portion by means of the nut 38, within which is the recess 39 into which the spring 40 fits, the other end of this spring having its bearing against the nut 37 and serving to normally hold the valve seated against its seat 32. The upper portion 2 of the main casing is similarly provided with a valve 41, which is similar to valve 30 of the lower casing. This valve operates within chamber 42, which is closed by nut 43. Valve 41 is provided with valve stem 44, similar to valve stem 35.

As is most clearly shown in Fig. 4, the side of chamber 4 has an opening 45 which is closed by the plate 46, held in position by screws 47. Integral with the plate 46 is the bracket 48 to which the lever 49 is pivotally attached. The spindle 11 is provided with a recess 50, into which the lever 49 is adapted to fit. This recess has two straight sides 51 and 52 which meet at an angle. It is evident that when the lever 49 is within the recess 50, as shown in Fig. 4, the valve 41 will remain seated, but if the spindle 11 were rotated in a clockwise direction the lever 49 would be forced to the right and the valve 41 would be unseated from its seat 53, and communication would be established between chambers 42 and 54. On the other hand, if the spindle 11 were rotated from the position shown in Fig. 4 in a counter-clockwise direction the lever 49 would still be within the recess 50 until the side 52 became parallel with the axis of the lever 49, after which the lever 49 would, of course, be moved to the right. A similar lever 55 is provided in connection with the valve 30, as shown in Figs. 2 and 5. The spindle 11 is provided with a recess 56, having the straight portions 57 and 58. The construction is such that while the sides 51 and 52 of the recess 50 are in the position shown in Fig. 4, the sides 57 and 58 of the recess 56 are in the position shown in Fig. 5. It is thus evident that if the spindle 11 were rotated in a clockwise direction the lever 49 would be moved to the right, whereas, the lever 55 would be unaffected, whereas on the other hand, if the lever were rotated in a counter-clockwise direction the lever 55 would be moved to the right, whereas, the lever 49 would be unaffected.

As shown in Figs. 2 and 3, a port 59 leads from the bottom of chamber 3, this port being provided with a notch 60. Port 59 communicates with passage 61, which passes upwardly through the portion 1 of the main casing, and, as shown in Figs. 2 and 4, continues through portion 2 of the main casing and then passes within the wall of the casing to communicate with valve chamber 42. The portion 1 of the main casing is pro- 130

vided with a boss 62, through which is the threaded passage 63 adapted for connection with a suitable exhaust pipe. Communicating with the passage 63 is the passage 64, which, as shown in Fig. 3, passes upwardly and in a circular direction through the wall of the portion 1 and opens into chamber 4 within the portion 2 of the main casing.

Because of the fact that each of the ports 10, 25 and 59 is provided with a notch, as above set forth, it is evident that whenever the slide valve 12 is actuated to afford a pneumatic connection through either of said ports, that the communicating passage of 15 which said port forms a part, is gradually increased as the valve 12 opens the port more and more. Inasmuch as I provide valves 30 and 41, which are serially disposed relative to the valve 12, I secure an arrangement wherein one valve positively prevents the passage of air and another valve serially disposed relative thereto, accomplishes the graduating or "wire-drawing" of the air. The spindle 11 may, if desired, be provided 25 with a central bore 11^a, for the reception of oil, this central bore communicating with a plurality of radial lubricating channels 11^b, as shown in Fig. 2.

Having thus described the construction 30 of my improved engineer's valve, the operation of the same may now be readily understood. When the handle 7 is placed in its central position, as shown in Fig. 2, the levers 49 and 55 will be within the recesses 35 50 and 56 of the spindle 11, and the valves 41 and 30 will remain seated. The slide valve 12, as shown in Fig. 6, will meanwhile cover the ports 25 and 59. The valve 30 being seated it will be clear that no air can 40 pass from the pipe member 21, which is connected with the main reservoir, into the chamber 3, and the port 25 being covered by the slide valve 12, no air can flow from the chamber 3 into the pipe portion 20, which is 45 connected with the brake pipe. Let us now assume that it is desired to make an application of the brakes by causing air to flow from the main reservoir to the brake pipe. The valve handle 7 is moved to the right or 50 in a counter-clockwise direction, thereby causing the lever 55 to be moved to the right and unseating connecting valve 30. Air is thereby allowed to flow from the pipe portion 21 through passage 27 into valve 55 chamber 28, then through chamber 33 into the chamber 3. Simultaneously, the slide valve 12 is moved so that port 59 is uncovered and the air in chamber 3 flows through passage 61 to the valve chamber 42, but inasmuch as the valve 41 remains seated this air can go no farther. As the slide valve 12 is moved farther in a counter-clockwise direction the notch 26 is uncovered and air will then flow into passage 24, which is in 60 direct connection with pipe member 20

which leads to the brake pipe. Thus, after the first application of the brakes the chamber 3 is relieved from main reservoir pressure by the closure of the valve 30, when the operating handle is returned to its normal or lap position. The pressure in the chamber 3 resulting from the application of the brakes is quickly equalized with the pressure in the passage 24, since the valve 12 is not a tight fit on its seat, such valve 12 being employed only to control the rapidity of pressure supplied to the chamber 24, and thus to the pipe 20, when the brakes are set. By this means a much cheaper construction of the valve 12 is permitted than is the case where this valve is depended upon to protect the chamber 24 and pipe 20 from the pressure of air contained in the body portion of the valve casing. Let us now suppose that it is desired to release the 85 brakes. The handle 7 is moved to the left of its central position or in a clockwise direction and the lever 49 is moved to the right, thereby unseating the valve 41. The air which is contained in passage 61 now 90 passes through chambers 42 and 54 into chamber 4, and then through passage 64 to passage 63 which is connected with atmosphere. As the valve handle continues to be moved to the left, the port 25 is uncovered, thereby allowing the air in the brake pipe to pass through passage 24 and port 25 into the chamber 3. Connecting valve 30 meanwhile remains seated, as explained above, so that there is no communication between chamber 3 and the main reservoir. As the handle 7 is moved still farther to the left the notch 60 in port 59 is uncovered and air within chamber 3 passes through port 59 into passage 61, to valve 10 chamber 42, then to chamber 54 into chamber 4, and from thence through passage 64 to the atmosphere. When it is desired to discontinue the release of the brakes the handle 7 is again moved toward its central 11 position until the port 59 is covered, thereby preventing further passage of air from chamber 3, although chamber 3 still remains in communication with the brake pipe. A further release of the brakes may, of course, 11 readily be obtained by again moving the handle 7 to the left, thereby again uncovering the notch 60 and allowing the air to travel, as explained above, from chamber 3 to the atmosphere. It will thus be evident 12 that when applying the brakes the pressure in chamber 3 remains the same as in the main reservoir, whereas, in releasing the brakes the pressure remains the same as in the brake pipe. After the brakes have been 12 released and it is desired to make a further application of the brakes the pressure is, of course, again raised in chamber 3 to that main reservoir, whereas, in releasing the connecting valve 30 prior to uncovering the 13

notch 26 in the port 25. It is evident that many changes could be made in the detail construction of the valve which I have described without departing from the spirit of my invention.

5 What I claim is:

1. In an engineer's valve, the combination of a main casing having inlet and outlet openings, a valve between said openings, a 10 spindle passing through said casing, and a separately pivoted lever operated by the movement of said spindle, said lever adapted to unseat said valve, thereby establishing communication between said openings.
- 15 2. In an engineer's valve, the combination of a main casing having inlet and outlet openings and an exhaust passage, a valve between said inlet and outlet openings, a second valve between said outlet opening and 20 said exhaust passage, a manually operated spindle passing through said main casing, and a separately pivoted lever associated with each of said valves, said levers being selectively operated by rotation of the spindle, each of said levers adapted to unseat its associated valve, thereby establishing connection between said inlet and outlet openings or between said outlet opening and the exhaust passage.
- 25 3. In an engineer's valve, the combination of a main casing having inlet and outlet openings, an exhaust passage, a chamber between the inlet and outlet openings and a second chamber between the outlet opening 30 and the exhaust passage, a valve in each of said chambers, a spindle passing through said casing, suitably disposed recesses in said spindle and a lever associated with each valve and engaging in said recesses, rotation 35 of said spindle adapted to selectively operate one of said valves, thereby establishing communication between said inlet and outlet openings or between said outlet opening and said exhaust passage.
- 40 4. In an engineer's valve, the combination of a main casing having inlet and outlet openings, an exhaust passage, a chamber between said inlet and outlet openings and a second chamber communicating with said first chamber, a valve between said inlet opening and said first chamber, a valve between said first and second chambers, a spindle passing through said casing, and a lever associated with each of said valves, rotation 45 of said spindle adapted to selectively operate either of said valves, thereby establishing connection between said inlet and said outlet openings or between said first and second chambers.
- 50 5. In an engineer's valve, the combination of a main casing having inlet and outlet openings, an exhaust passage, a first chamber between said inlet opening and said outlet opening and a second chamber between 55 said first chamber and said exhaust passage,
5. a spring controlled valve between said inlet opening and the first chamber, a second spring controlled valve between the first chamber and the second chamber, a rotatable spindle passing through said casing, suitably disposed recesses in said spindle and a lever associated with each valve, each of said levers engaging a recess in said spindle and adapted to be operated by the rotation of said spindle to selectively unseat either of said 70 spring controlled valves.
6. In an engineer's valve, the combination of a main casing having a first chamber therein, an inlet and outlet opening communicating with said first chamber, a second chamber communicating with said first chamber, and an exhaust passage communicating with said second chamber, a spring controlled valve between said inlet opening and said first chamber, a spring controlled valve between said first chamber and said second chamber, a spindle passing through said casing, a rotatable slide valve operated by said spindle, said slide valve adapted to interrupt communication between said first chamber and said outlet opening and between said first chamber and said second chamber, and a lever associated with each of said spring controlled valves.
7. In an engineer's valve, a main casing having a chamber therein, inlet and outlet openings in communication with said chamber, a second chamber communicating with said first chamber and an exhaust passage, a spindle passing through said casing, and a 100 rotatable slide valve operated by said spindle, said slide valve adapted to establish communication between said first chamber and said outlet opening and between said first chamber and said second chamber.
8. In an engineer's valve, a main casing having a chamber therein, inlet and outlet openings in communication with said chamber, a second chamber communicating with said first chamber and an exhaust passage, a spindle passing through said casing, and a rotatable slide valve adapted, when rotated in one direction, to establish communication between said first chamber and said second chamber in advance of establishing communication between said first chamber and said outlet opening, and, when rotated in the opposite direction, adapted to establish communication between said first chamber and said outlet opening in advance of establishing communication between said first chamber and said second chamber.
9. In an engineer's valve, the combination of a main casing having two separate port openings and an exhaust passage, a 130

- valve between said port openings, a valve between one of said port openings and the exhaust passage, a spindle passing through said casing, suitably disposed recesses in said spindle and a lever associated with each valve and engaging in one of said recesses, rotation of said spindle adapted to selectively operate one of said valves, thereby establishing communication between one of 10 said port openings and said exhaust passage.
10. In an engineer's valve, the combination of a main casing having an opening, a valve controlling said opening, a spindle passing through said casing, suitably disposed recesses in said spindle and a lever associated with said valve and engaging said recesses, rotation of said spindle adapted to 15 operate said valve.
11. In an engineer's valve, the combination of a casing having inlet and outlet openings, a valve between said openings, a spindle passing through said casing, a cam on the lower end of said spindle, and a separately mounted member engaging said cam and 20 operated by the movement of said spindle, said member adapted to unseat said valve, thereby establishing communication between said openings.
12. In an engineer's valve, the combination of a casing having inlet and outlet open- 25
- ings, a valve between said openings, a spindle mounted in said casing and operable from the outside, said spindle having a recess, and a separately mounted member engaging in said recess and adapted to unseat said 30 valve, whereby communication is established between said openings.
13. In an engineer's valve the combination of a main casing having inlet and outlet openings and an exhaust passage, a valve 35 between said inlet and outlet openings, a second valve between said outlet opening and said exhaust passage, a manually operated member passing into said casing and a separately mounted member associated 40 with each of said valves, said separately mounted members being selectively operated by the operation of said operating member, each of said separately mounted members adapted to unseat its associated valve, thereby 45 establishing connection between said inlet and outlet openings or between said outlet opening and the exhaust passage.
- In witness whereof, I hereunto subscribe my name this 4th day of March, A. D. 1910. 50
- BURTON S. AIKMAN.
